CLAIM

The ornamental design for an industrial robot, as shown and described.

DESCRIPTION

FIG. 1 is a left side perspective view of an industrial robot embodying our new design;

FIG. 2 is a rear elevational view with the arm in an alternate position;

FIG. 3 is a front elevational view of FIG. 2;

FIG. 4 is a bottom plan view of FIG. 2;

FIG. 5 is a top plan view of FIG. 2;

FIG. 6 is a left side elevational view of FIG. 2, the right side being a mirror image.

FIG.1

FIG. 2

FIG. 3

FIG. 4

FIG. 5

FIG. 6
